Attorneys

UNITED STATES PATENT OFFICE.

JOHN D. BEATTY, OF IVANHOE, NORTH CAROLINA.

TENSION DEVICE.

Application filed October 5, 1923. Serial No. 666,769.

To all whom it may concern:

Be it known that I, JOHN D. BEATTY, a citizen of the United States, residing at Ivanhoe, in the county of Bladen (R. F. D.) 5 and State of North Carolina, have invented a new and useful Tension Device, of which the following is a specification.

The device forming the subject matter of this application is a connector of that 10 general sort in which two relatively movable members are drawn together by the action of a resilient loop, and the invention aims to provide novel means whereby the loop may be renewed readily, the device being 15 capable of many uses, and adapted to be put on suspenders and garments, to be used in place of dead-eyes and turnbuckles in the setting-up of the standing rigging of vessels, on agricultural implements, and, generally, 20 wheresoever a tension device may be required.

It is within the province of the disclosure to improve generally and to enhance the utility of devices of that type to which the 25 invention appertains.

With the above and other objects in view, which will appear as the description proceeds, the invention resides in the combination and arrangement of parts and in the 30 details of construction hereinafter described and claimed, it being understood that, within the scope of what is claimed, changes in the precise embodiment of the invention shown, can be made, without departing from 35 the spirit of the invention.

Figure 1 is an elevation showing a device constructed in accordance with the invention, parts being broken away, and parts appearing in section; Figure 2 is a section on the line 2—2 of Figure 1; Figure 3 is a fragmental perspective review showing one 40 of the cover plates; Figure 4 is an elevation showing a modified form of the invention, parts being broken away, and parts appearing in section.

Referring to Figures 1, 2, and 3, there are shown relatively movable members 1 which may be of semicircular outline, if desired, although this detail is not insisted upon. 45 The member 1 comprises a body 2 having an internal projection 3, there being grooves 4 in the bodies 2 about the projections 3. A resilient loop 5 is engaged about the projections 3 and may be in the form of a retractile helical spring. Covers 6 are

secured to the bodies 2 of the members 1 by attaching elements 7, entering the projections 3, the covers 6 having flanges 8 located at the ends of the bodies 2 and forming abutments when the members 1 are brought 60 together by the action of the resilient loop 5, the flanges 8 having openings or notches 9 through which the loop 5 passes. The members 1 are supplied at their ends with connectors 20, which may be swiveled eyes 65 or equivalent devices.

It will be obvious that when the members 1 are separated, the loop 5 will tend to draw them together. The covers 6 may be removed at any time to permit the loop 5 to 70 be replaced, should the loop lose its resiliency after a period of use.

In Figure 4 of the drawing, parts hereinbefore described have been designated by numerals previously used, with the suffix 75 "a". The modification consists in elongating each of the movable members 1^a over the showing of the corresponding part 1 in Figure 1. Further, the internal projection is in the form of a pulley 10 journaled at 80 20 on the body 2^a of the movable member 1^a.

I claim:—

1. A device of the class described, comprising relatively movable members, each of which has a pulley journaled therein, and 85 a resilient loop engaged with the pulleys, each of said members comprising separable parts permitting the loop to be removed and renewed.

2. A device of the class described, comprising relatively movable members, each of which comprises a body having an internal projection, a resilient loop engaged with the projections, covers, and means for connecting the covers movably to the bodies to permit the removal and the renewal of the loop. 95

3. A device of the class described constructed as set forth in claim 2, and further characterized by the fact that the covers have flanges overlapping the ends of said 100 members and forming cooperating abutments, the flanges having openings for the passage of the loop.

4. A device of the class described constructed as set forth in claim 2, and further 105 characterized by the fact that the projections are in form of pulleys journaled in said members.

5. A device of the class described, constructed as set forth in claim 2, and further 110

characterized by the fact that the projections are in the form of pulleys journaled in said members, the covers having flanges overlapping the ends of said members and forming cooperating abutments, the flanges having openings for the passage of the loop.

In testimony that I claim the foregoing as

my own, I have hereto affixed my signature in the presence of two witnesses.

JOHN D. BEATTY.

Witnesses:

R. J. HESTER,
RALPH BORING.
